DESIGN FOR A PNEUMATIC TIRE

Elliott S. Ewart, St. Clair Shores, Mich., assignor
to United States Rubber Company, New York,
N. Y., a corporation of New Jersey

Application March 21, 1940, Serial No. 91,127

Term of patent 14 years

To all whom it may concern:

Be it known that I, Elliott S. Ewart, a citizen of the United States of America, residing in St. Clair Shores, county of Macomb, State of Michigan, have invented a new, original, and ornamental Design for a Pneumatic Tire, of which the following is a specification, reference being had to the accompanying drawing, forming part thereof, wherein:

Figure 1 is a side elevational view of a portion of a tire embodying my new design;

Figure 2 is a transverse sectional view, taken along line II—II of Figure 4;

Figure 3 is a detail view, in section, taken along line III—III of Figure 2; and

Figure 4 is a plan view of a portion of the tire.

I claim:

The ornamental design for a pneumatic tire, as shown.

ELLIOTT S. EWART.
